US0D1069016S

(12) **United States Design Patent** (10) Patent No.: **US D1,069,016 S**
(45) Date of Patent: ** Apr. 1, 2025

(54) **FOLDING GUN**

(71) Applicant: **Magpul Industries Corp.**, Austin, TX (US)

(72) Inventors: **Nicholas Kielsmeier**, Denver, CO (US); **Brian L. Nakayama**, Arvada, CO (US); **Jeremy M. Fieste**, Lafayette, CO (US); **Michael T. Mayberry**, Denver, CO (US)

(73) Assignee: **Magpul Industries Corp.**, Austin, TX (US)

(**) Term: **15 Years**

(21) Appl. No.: **29/786,817**

(22) Filed: **Jun. 2, 2021**

(51) LOC (15) Cl. 22-01

(52) U.S. Cl.

USPC **D22/104**; D14/418; D21/572; D21/573; D21/574

(58) **Field of Classification Search**

USPC D14/418; D21/324, 572, 573, 574, 575; D22/103, 104, 105, 199

CPC F41C 23/04; F41C 23/12

See application file for complete search history.

(57) **CLAIM**

The ornamental design for a folding gun, as shown and described.

DESCRIPTION

FIG. 1 is a front left top perspective view of the folding gun in a deployed configuration;

FIG. 2 is a front view of the folding gun in FIG. 1;

FIG. 3 is a rear view of the folding gun in FIG. 1;

FIG. 4 is a right side view of the folding gun in FIG. 1;

FIG. 5 is a left side view of the folding gun in FIG. 1;

FIG. 6 is a top view of the folding gun in FIG. 1;

FIG. 7 is a bottom view of the folding gun in FIG. 1;

FIG. 8 is a rear right bottom perspective view of the folding gun in FIG. 1; and,

FIG. 9 is a front left top perspective view of the folding gun in a folded configuration.

The shade lines in the figures show contour and not surface ornamentation.

The broken lines showing portions of the design in all figures are included for the purpose of illustrating environment and do not form a part of the claimed design.

1 Claim, 7 Drawing Sheets
